UNITED STATES PATENT OFFICE.

FRANK LEGH SLAZENGER, OF NEW YORK, N. Y.

STRENGTHENING DEVICE FOR RACKETS.

1,035,105.

Specification of Letters Patent.

Patented Aug. 6, 1912.

Application filed January 30, 1912. Serial No. 674,259.

To all whom it may concern:

Be it known that I, FRANK LEGH SLAZENGER, a citizen of the United States, residing at New York, in the county of New York and State of New York, have invented certain new and useful Improvements in Strengthening Devices for Rackets; and I do hereby declare the following to be a full, clear, and exact description of the invention, such as will enable others skilled in the art to which it appertains to make and use the same.

My invention relates to new and useful improvements in rackets adapted to be used in playing games, such as rackets, squash, court tennis, etc.

The object of my invention is to provide means for effectively strengthening the head of the racket.

Other objects and advantages will be hereinafter made clearly apparent in the specification, and pointed out in the claims.

In the accompanying drawings I have shown the preferred form which my invention may take.

In said drawings, Figure 1 is an elevation showing a racket constructed in accordance with my invention. Fig. 2 is a detail sectional view, as seen on line 2—2, Fig. 1, and, Fig. 3 is a detail sectional view as seen on line 3—3, Fig. 1.

Referring to the drawings, in which similar reference numerals designate corresponding parts throughout the several views, 1 is the handle of my device having a head 2 at one end thereof. In practice the head 2 is formed of a continuous strip of material, the ends of said strip being extended and forming part of the handle.

In practice the head 2, being formed from a single strip of material, is often broken. In order to strengthen the head I take a strip 3 of material, preferably of about one-sixteenth of an inch in thickness, and the width of the head, and wind said strip upon a form of shape similar to the shape of the head. In the drawing I have shown a strengthening member formed by winding strip 3 four complete times around a form.

The ends of the strip 3 are preferably arranged at the end of the racket adjacent the handle, the opposite ends of said strip

being correspondingly tapered and oppositely disposed so that the thickness of the completed strengthening member will be 55 the same throughout its length. When forming the strengthening member the overlapped portions thereof are glued so that when the strengthening member has been formed it will have the appearance of a 60 single strip of material. It is a well known fact that a strengthening device formed from a thin strip of material wrapped several times, will be stronger than a strengthening device formed from a single strip 65 of material of the same width as the device formed from the plurality of wrappings.

When the strengthening member has been formed as above described it is removed 70 from the form and the surplus glue scraped therefrom and the device secured in any desired manner inside the head of the racket. The head, handle and strengthening device are then scraped and varnished or finished 75 in any other desired manner and the head is then strung, as indicated at 4.

By my invention I am enabled to secure a racket of great strength and which may be made of the same weight and balance as 80 the racket usually used.

While I have shown the preferred form of my invention, I desire it to be understood that I may make certain modifications therein without departing from the spirit 85 and scope of my invention.

What I claim as new is:

1. A strengthening device for rackets, etc., comprising a strip of material having a plurality of turns in the form of said racket, 90 said strengthening device adapted to be secured inside the head of a racket, the ends of said strip of material being correspondingly tapered and oppositely disposed.

2. The combination with a racket having 95 a head and a handle; of a strengthening device for the head of said racket comprising a single strip of material wrapped a plurality of times in the form of said head, said strengthening device being positioned 100 in said head.

3. The combination with a racket having a head and a handle; of a strengthening device for the head of said racket comprising

a single strip of material wrapped a plurality of times in the form of said head, said strengthening device being positioned in said head, the ends of the strip forming said strengthening device being correspondingly tapered and oppositely disposed.

In testimony whereof I have signed my

name to this specification in the presence of two subscribing witnesses.

FRANK LEGH SLAZENGER.
